(57) **CLAIM**

We claim the ornamental design for an automotive vehicle dashboard, as shown and described.

DESCRIPTION

FIG. 1 is a left-perspective view of an automotive vehicle dashboard, of the new design;

FIG. 2 is a right-perspective view thereof;

FIG. 3 is a top view thereof;

FIG. 4 is a front view thereof;

FIG. 5 is a side view thereof; and,

FIG. 6 is a side view thereof, taken opposite that of FIG. 5. The broken lines (e.g., the vent handles) are for environmental illustrative purposes only and form no part of the claimed design.
